COMBINED DOUGH STORAGE RECEPTACLE AND COOKY MOLD

Naomi M. Goldschmidt, Milwaukee, Wis.

Application March 22, 1952, Serial No. 19,017

Term of patent 14 years

(Cl. D44—1)

To all whom it may concern:

Be it known that I, Naomi M. Goldschmidt, a citizen of the United States, residing in the city of Milwaukee, in the county of Milwaukee and State of Wisconsin, have invented a new, original, and ornamental Design for a Combined Dough Storage Receptacle and Cooky Mold, of which the following is a description, reference being had to the accompanying drawing forming a part thereof.

In the drawing:

Fig. 1 is a top perspective view of a combined dough storage receptacle and cooky mold embodying my new design and showing the same with the cover removed and the feed plunger partially visible, and;

Fig. 2 is a central longitudinal vertical section through the receptacle and the attached cover.

I claim:

The ornamental design for a combined dough storage receptacle and cooky mold, substantially as shown.
